NECKTIE

Siegfried F. Scheib, 2701 N. Mozart St., Chicago, Ill.

Filed Dec. 11, 1959, Ser. No. 58,636

Term of patent 3½ years

(Cl. D3—16)

Figure 1 is a front perspective view of a necktie showing my new design. The opposite sides of the tie are conventional and unornamented.

The dominant feature of my design resides in the ornamentation shown on the large end of the necktie.

I claim:

The ornamental design for a necktie, as shown and described.
